HERMANN WINDRATH AND HUBERT EICKEN, OF GREVENBROICH, GERMANY.

DYEING APPARATUS.

1,021,811.

Specification of Letters Patent.

Patented Apr. 2, 1912.

Application filed November 2, 1909. Serial No. 525,901.

To all whom it may concern:

Be it known that we, HERMANN WINDRATH and HUBERT EICKEN, subjects of the German Emperor, and residents of Grevenbroich, 5 Germany, have invented certain new and useful Improvements in and Relating to Dyeing Apparatus, of which the following is a specification.

This invention relates to a dyeing apparatus comprising a carrier for the textile materials and a bell for removing the air from the material to be dyed.

The pressing apparatus differs from others in the use of suction, rather than pressure for causing the dyeing liquid to circulate through the fabric being dyed. It is well-known that fluid, under pressure, tends to separate the members of the vessel or pipe containing it; and that the same, under 20 suction, tends to more closely unite said members. It is also known that mechanical fastening means are essential elements in a fluid-tight joint, subjected to internal pressure, and that in order to disunite such 25 joints, physical force is essentially exerted. To the contrary: where suction is exerted within a hollow tube or chamber, having joints, the tendency is to bind the joints more closely and firmly together. The principle of suction is therefore employed in the 30 present invention, for the two-fold purpose of providing a joint, of maximum efficiency, between the tank, which holds the liquid dye, and the pipes through which the dye 35 circulates; and to provide such a joint, that requires only a release from suction and from the pressure resulting from gravity, for disconnecting the joint.

We attain the foregoing objects by the 40 mechanism illustrated in the accompanying drawings, in which, similar reference characters designate similar parts, and in which—

Figure 1 is a view in elevation of the preferred form and embodiment of our invention, certain parts being shown in section. Fig. 2 is a top, plan view of the tank, the pump and connections.

Referring now to the drawings: A carrier 50 A, is provided for holding the material, to be dyed which is here represented, by spools or bobbins of yarn or the like, at a, which are hereinafter to be referred to as textile. The manner in which this textile is held by 55 the carrier, forms no part of this invention and will not be described. The carrier A is

preferably of cylindrical form, the top of the cylinder being closed, and the bottom having an annular opening d, therein. Intermediate of the cylinder, is the horizontally disposed partition a' having an opening centrally thereof; and a pipe S, registering with the opening, extends to the same horizontal plane as that of the bottom of the carrier A, thereby forming an annular 60 space D between the carrier and the pipe. A bell P which covers the carrier, may be arranged for raising and lowering, with relation to the carrier, for convenience in placing and removing the textile. Raising 65 and lowering means are indicated at P'. At P' is indicated a fluid-tight joint between the bell and the carrier. A tank F, of sufficient size to receive the bell, has openings C' and E' through the bottom thereof, and 70 adapted to register with the opening d and S', respectively, when the bell and carrier are lowered into the tank F. A suction pump indicated at G, is connected with the openings E' and C' by suction and delivery 75 pipes E' and C', respectively, so that when the openings d and S' are in registration with the openings C' and E', and the bottoms of the pipe S and carrier B rest upon the bottom of the tank, communication is 80 established between the pump and carrier, which, latter, is provided with perforations a² and a³. The flexible pipe Z communicates with the interior of the bell and with a 85 vacuum tank, indicated at V, in which a 90 vacuum may be sustained by any proper means. A stop cock H is interposed between the pipe Z and the vacuum tank, for establishing or interrupting suction through the 95 pipe Z.

In operation, the carrier B is first loaded with textile, and the tank F is supplied with the proper amount of dyeing fluid. The bell P is then seated on the carrier as shown. The bell and carrier are then lowered into the tank, until they are seated on the bottom thereof, and the openings S' and d, register with the openings E' and C', respectively. During the operation of lowering the bell, the cock H is opened, so that the air therein 100 gives place to the dyeing liquid. The suction, produced by the vacuum means, should be sufficient to so rarefy the air in the bell so that the dyeing liquid has free access to penetrate between the fibers of the textile, and thus assure a uniform coloring of the same. This vacuum also causes the external 105 110

pressure of the air to seat the carrier more firmly on the bottom of the tank and produces a tighter connection between the openings S' , d and E' , C' . This tightening effect is increased by the action of the suction pump G , which causes the dyeing liquid to circulate through the pipes E and C , and through the carrier B pipe S an annular space D , in the direction indicated by the arrows, owing to the outlet S' being less commodious than the inlet d and therefore offering greater resistance to the downward current than is offered to the upward current. Now, considering the bell and carrier to be in the lowered position, and resting on the bottom of the tank, the bell and carrier being full of the dyeing liquid: the suction, from the pump, draws the liquid through the pipes S and E and delivers it again into the tank, through the pipe E and annular space D , whence it passes through the perforations a^2 , between and through the textile and back through perforations a^3 , and is again sucked down through the pipe S . Thus a continual circulation of the liquid is maintained and a continual suction is exerted from two sources, by which a secure and convenient connection of the carrier with the suction pipes is assured.

We claim—

1. In a dyeing apparatus for textile fabric, a tank adapted to contain dyeing liquid and having an inlet and an outlet in the bottom thereof, a hollow, perforated carrier for the fabric adapted to be lowered into said tank and having ports adapted to register with said inlet and outlet ports, a bell removably secured around said carrier and adapted to be lowered therewith into said tank, and suction means communicating with the inlet and outlet for establishing a current of the liquid through the carrier and bell and fabric.
2. In a dyeing apparatus of the kind described the combination with the circular dye tank and the carrier for the material, this carrier having the shape of a hollow

cylinder adapted to movably and tightly engage the said dye tank, means for raising and lowering the said carrier in said tank, a bell provided over the said carrier and adapted when the latter is lowered to dip with its lower edge in the dye contained in the tank thereby sealing the carrier, a vacuum plant, a flexible pipe connection between the said vacuum plant and the said bell, a cock in the said flexible pipe connection, whereby the air can be withdrawn from the bell, the carrier and the material, when the carrier is dipped into the dye, while when the carrier is removed from the tank, the air is prevented from arriving too rapidly at the material, substantially as and for the purpose described.

3. A dyeing apparatus for textile fabric comprising a tank adapted to contain dyeing liquid and having an inlet and an outlet in the bottom thereof, a hollow, perforated carrier adapted to be lowered into said tank and having openings adapted to register with said inlet and outlet, said carrier having a horizontal partition dividing it into a lower and upper chamber, a pipe communicating with the upper chamber, a bell surrounding the carrier and having air exhaust means connected therewith, and suction means connected with said inlet and outlet for establishing a current of said liquid through the textile fabric.

4. A dyeing apparatus for textile fabric comprising a tank for containing dyeing liquid, a carrier for textile fabric, a bell surrounding the carrier and fabric, means co-acting with the liquid for exhausting air from the textile fabric and means for establishing a current of the liquid through the fabric while the air is exhausted therefrom.

In testimony whereof we have hereunto set our hands in presence of two witnesses.

HERMANN WINDRATH.

HUBERT EICKEN.
